WILLIAM B. SLAUGHTER, JR., AND RALPH A. GAERTNER, OF LOS ANGELES, CALIFORNIA,
ASSIGNORS TO PETER E. SPELLACY, OF LOS ANGELES, CALIFORNIA.

FUEL-PUMP FOR SEMI-DIESEL ENGINES.

1,260,724.

Specification of Letters Patent. Patented Mar. 26, 1918.

Application filed October 30, 1916. Serial No. 128,609.

To all whom it may concern:

Be it known that we, WILLIAM B. SLAUGHTER, Jr., and RALPH A. GAERTNER, citizens of the United States, residing at Los Angeles, in the county of Los Angeles and State of California, have invented new and useful Improvements in Fuel-Pumps for Semi-Diesel Engines, of which the following is a specification.

10 This invention relates to a fuel pump, and particularly pertains to a pump for delivering a liquid fuel to the explosive cylinders of engine of the semi-Diesel type.

It is an object of this invention to provide 15 a fuel pump which embodies a reciprocating plunger adapted to be controlled to vary the length of its stroke without interruption of the operation of the pump.

Another object is to provide a series of 20 pumps feeding a series of cylinders, so that the capacity of each pump may be manually and independently adjusted during the operation to bring all the cylinders to a desired harmonious efficiency.

25 Another object is to control a series of oil pumps feeding a series of cylinders simultaneously by a speed operated governor and provide means for independent manual adjustment of each pump so that the cylinders 30 may be tuned or harmonized to a desired pitch or efficiency and so that the energy may be raised or lowered.

Another object is to provide an adjustable 35 timing mechanism for harmonizing the action of the pumps with the action of the cylinders, as to exploding various oils.

Another object is to provide a simple 40 operating mechanism which will act in synchronism with the movement of the engine pistons to deliver the fuel charge at a predetermined interval.

Another object is to provide a simple 45 pump control mechanism which may be easily manipulated to vary the plunger stroke as the mechanism is in operation.

Another object is to provide adjustable means for timing the pump in relation to the movement of the engine pistons as required

by the various grades of fuel used and the particular engine designed.

It is a further object to provide a pump and operating mechanism therefor which is simple in its construction and which will prevent any one of the fuel pumps from delivering fuel when it is desired to discontinue the combustion of fuel within a corresponding engine cylinder.

Other objects will appear hereinafter.

The invention is illustrated, by way of example, in the accompanying drawings, in which:

Figure 1 is a view in side elevation illustrating an engine of the semi-Diesel type as fitted with the fuel pump and adapted to receive fuel therefrom.

Fig. 2 is an enlarged view in side elevation illustrating the complete pump and driving mechanism.

Fig. 3 is a view in vertical section and elevation as seen on the line 3-3 of Fig. 2, 70 and illustrates the correlation existing between the various vital elements of the pump mechanism.

Fig. 4 is a view in section as seen on the line 4-4 of Fig. 3 and illustrates the eccentric pin formation.

Fig. 5 is a view in end elevation illustrating the arrangement of the eccentric portions on the eccentric pin.

Referring more particularly to the drawings, 10 indicates the crank shaft of a semi-Diesel engine which is provided with a series of cylinders 11 adapted to be supplied with a liquid fuel through conduits 12 leading from a fuel pump 13 secured upon the crank case of the engine. The pump is formed with a series of cylinders 14 which correspond in number to the cylinders of the engine and are in communication therewith through the conduits 12. All of the cylinders 90 are alike both as to construction and operation.

Reference being had to Fig. 3 of the drawings, it will be seen that the cylinder 14 is formed with a bore 15 adapted to receive a 95 cylindrical reciprocating plunger 16. This

plunger extends downwardly through a stuffing box 17 and terminates at its lower end with a disk shaped head 18. The plunger is intended to normally be drawn downwardly by the action of an expansion coil spring 19 positioned around the plunger and between the stuffing box and the head 18.

As a means for mechanically lifting the plunger, a push rod 20 is provided and reciprocates in alignment with the plunger 16 and therebeneath. The pump frame is formed with a suitable bearing 21 along which the push rod may travel, an expansion spring being provided to maintain the plunger in its lowermost position as limited by rocker arm 23. The rocker arm 23 is pivotally mounted for vertical movement upon a pivot shaft 24 secured to the pump frame. The arm extends beneath the push rod 20 and receives motion imparted indirectly from an oscillating arm 25. The arm 25 is pivoted to the pump frame upon a shaft 26 in vertical alignment with the shaft 24 and is fitted at its lower end with a roller 27. This roller is adapted to bear upon one of a series of eccentric cams 28 which are formed at given intervals around the periphery of a cam sleeve 29. The swell of each cam, as here shown, is disposed in relation to the remaining cams so that each of the pump mechanisms will be actuated in a single revolution of the sleeve, although other arrangements of the cams may be made if desired. The sleeve is tubular and is adjustably fitted upon the crank shaft 10 of the engine, a flange 30 being provided for the purpose. The flange 30 is formed with a series of perforations 31 and slots 32 through which cap screws 33 extend to engage a fixed flange 34 by which the sleeve is driven. The flange 34 is formed with a series of threaded apertures through one of which the set screw 33' may extend to positively maintain the flanges in a given relation to each other. After the screw 33' has been placed in position the lock screws 33 are tightened to prevent further movement of the flanges in relation to each other. The flange 34 is secured by a tapered pin 35 to the shaft 10, although other securing means might be found desirable.

As a means for varying the length of stroke made by the plunger while the oscillating arm 25 describes a given movement, a slidable wedge 36 is pivotally mounted upon an eccentric pin 37 secured at the end of the crank arm 38. Reference being had to Figs. 4 and 5 it will be seen that the pin 37 is formed with a large head portion 49 formed with a serrated edge adapted to engage a stop pin 50 which is detachably mounted within the arm 38. Adjacent this head is a cylindrical body portion 52 concentric therewith and concentrically ar-

ranged in relation to a threaded end portion 51. Between the portions 51 and 52 an eccentric length is formed and adapted to register with the bore through the wedge 36. It will be seen by this arrangement that the stroke of each pump may be individually adjusted by rotating the eccentric pin to advance or retard the wedge 36. The arms 38, one for each pump, extend downwardly from a shaft 39, to which they are rigidly fixed, and the shaft 39 is adapted to be oscillated by a suitable mechanism secured to the shaft, and actuated by the engine governor. In this manner each wedge 36 may be advanced toward and away from the vertical axis of the pivot shafts 24 and 26, and due to the fact that they are wider than the distance between the adjacent faces of the arms 23 and 25, the stroke will be varied, by manual adjustment and by the action of the governor.

It may be found desirable to discontinue the operation of one or more cylinders of the engine and at such a time the fuel supply may be stopped by manipulation of a lever 40 pivotally mounted upon a shaft 41 adjacent the head 18 of the plunger 16. This lever is formed with a bifurcated end portion 42 which spans the plunger 20 and is adapted to bear against the lower face of the head 18. Projections 42' are formed on the lower faces of the bifurcated end portions of the lever 40. These projections normally bear upon the face of the main casting or housing to which the mechanism of the apparatus is secured. In this manner the bifurcated portion of the lever will be limited in its downward travel and will thus limit the downward movement of the plunger 16 and the expansion of the plunger spring 19. A lock nut 43 is provided to engage the handle of the lever 40 and hold it to prevent the plunger 20 from striking the head 18 of plunger 16 and actuating pump.

Fuel is supplied the pumps by a conduit 44 which connects with a fuel chamber 45 formed upon a pump casing adjacent the pumps. A screen cup 46 is mounted within said chamber and prevents fuel sediment from passing into tubular stem 47 which connects with the pump by means of a connecting conduit 48. The fuel passes from the pump to the engine through the conduit 49 and a check valve mounted within the pump head.

It will be understood that the foregoing description of the pump operating mechanism is confined to a single pump unit and that a mere multiplication of these units is required to accommodate a multiple cylinder engine.

When the engine is started the crank shaft 10 is rotated and will in turn rotate the sleeve 29 which is secured to it by the

flanges 30 and 34. The sleeve is adjusted upon the shaft by means of the bolts 33 which extend through the slotted openings 32 in the flange 30 and permit a limited independent rotatable movement of sleeve in relation to the crank as has been previously described. This arrangement allows the fuel to be injected into the cylinder at any predetermined interval in relation to the 10 piston movement. As the sleeve rotates with the shaft the eccentrics 28 will successively oscillate the arm 25 and will impart motion to the arm 23 by the stroke wedge 36 interposed therebetween. As the arms move the 15 wedge will oscillate upon the pivot pin 37 which has been adjusted to meet the fuel requirements of the cylinder. As the arm 23 is moved upwardly the lower push rod 20 will be reciprocated and will engage the 20 head 18 of plunger 16 to force it upwardly within the bore 15 and thus force the liquid fuel out through the valve 50 to the engine by way of the conduit 12. To increase or 25 decrease the volume of fuel delivered to the engine, the control arm 38 is horizontally swung to move the wedge 36 toward the vertical axis of the pivot shafts 24 and 26 thus increasing the stroke of the piston.

When the fuel supply is to be discontinued from one or more of the cylinders the corresponding lever arm 40 may be pressed downwardly and locked beneath the nut 43 to prevent actuation of the pump plunger effected thereby.

35 It will thus be seen that the fuel pump here provided is decidedly simple in construction and possesses few parts liable to become objectionably warm and that furthermore a simple stroke changing mechanism is provided as well as means for instantaneously rendering the pump units inoperative.

Especial attention is called to the means for adjustably timing the action of the 45 pumps relative to the action of the cylinders, and comprising the cam sleeve 29 carrying the pump driving cams 28, said sleeve being loosely mounted upon the crank shaft 10, the flange 34 being fixed upon the 50 crank shaft and the flange 30 being fixed to the sleeve, and the flange 30 being adjustably connected to the flange 34 by bolts through slots. This is an important feature. It provides means for adjustably timing all 55 the pumps simultaneously to fit the actions of the cylinders, as to exploding various oils and as to the firing of the charges.

Attention is also called to the means for 60 manually varying the effective stroke of a pump during its operation and consisting of the wedge 36 and the eccentric pin 37, and the coöperating elements. This construction also provides manual means for independently varying the effective stroke

of each of a series of pumps connected to 65 a series of cylinders and during the operation, so as to bring all the cylinders to a desired harmonious efficiency, and maintain that efficiency by a speed controlled governor, and raise or lower the efficiency by manual adjustment at will. 70

We claim:

1. In an oil pump, a pump plunger, a stuffing box around the pump plunger, a head upon the lower end of the pump plunger, a spring between the head and the stuffing box to withdraw the plunger, manually operated means for holding the plunger against withdrawal, thereby cutting the pump out of action, a push-rod mounted in 75 alinement with the plunger, a spring for moving the push-rod away from the plunger, a rocker arm under the push-rod, an oscillating arm below the rocker arm, means for operating the oscillating arm, a slide- 80 able wedge between the oscillating arm and the rocker arm, and manually operated means for adjusting the position of the slide- 85 able wedge so as to vary the stroke of the plunger. 90

2. In an oil pump, a pump cylinder, a pump plunger mounted in the cylinder, a head upon the plunger outside of the cylinder, a push-rod engaging the head, means for operating the push rod to operate the 95 plunger, a spring pressing the plunger toward the push rod, a lever pivotally mounted and connected to the head and adapted to limit the action of the spring, and a lock for the lever; so that the lever may be operated to raise the head and prevent withdrawal of the plunger, thereby cutting the pump out of action. 100

3. In an oil pump, a series of pump cylinders vertically mounted and discharging upwardly, pump plungers mounted in the cylinders and extending downwardly, heads upon the lower ends of the plungers, springs between the heads and the cylinders to withdraw the plungers, push-rods mounted in 105 vertical alinement below the heads and engaging the heads, means for operating the push-rods to operate the plungers, levers pivotally mounted and connected to the heads and adapted to limit the withdrawal 110 strokes of the plungers, and an independent means for each lever for holding the lever to hold the plunger against withdrawal so that each plunger may be independently operated to cut the pump to which it belongs 115 out of action. 120

4. In an oil pump, a series of pump cylinders vertically mounted and discharging upwardly, a pump plunger for each cylinder and extending downwardly, a spring for withdrawing each plunger, a push-rod for advancing each plunger, a spring for withdrawing each push-rod, a rocker arm under 125

each push-rod, an oscillating arm below each rocker arm, means for operating the oscillating arms simultaneously, a slideable wedge between each oscillating arm and the 5 corresponding rocker arm, an oscillating shaft, arms fixed upon the oscillating shaft, one for each sliding wedge; so that the sliding wedges may be simultaneously operated

by operating the shaft; and means for independently adjusting the connections between 10 the arms and the sliding wedges so as to vary the strokes of the pump plungers.

In testimony whereof we have signed our names to this specification.

WILLIAM B. SLAUGHTER, JR.
RALPH A. GAERTNER.
